PERFORATING DEVICE

Carl Funcke, Osterronfeld, near Kiel, Germany,
assignor of one-half to Max Muller, Ottweiler-
Saar, Germany

Application October 3, 1938, Serial No. 233,135
In Germany August 6, 1937

8 Claims. (Cl. 164—98)

The present invention relates to apparatus for periodically actuating a perforating tool or tools, with the aid of a control wheel, on the application for printing and other installations.

In known perforating devices of this kind the actuation of the perforating tools and of the feed wheel is effected during one and the same stroke of an operating member. In such devices difficulties are frequently experienced which cause injury to the sensitive parts of the device; automatic control of the perforating tools in predetermined periodicity is, therefore, hardly practicable.

The present invention avoids these difficulties by providing that an operating or feed member, is moved to and fro and in one direction of its movement actuates, by means of a coupling member controlled by the control wheel, a spring-loaded cutter bolt for moving the perforating tools, whilst in its other direction of movement the operating member advances the control wheel through a predetermined distance. The reciprocating operating member preferably has a driving part and a controlling part, the latter being provided with a one-way feed device, whilst the former consists of a laterally extending part of the operating member and acts on the cutter bolt through the coupling member. At the same time there is advantageously mounted, above the operating member provided with a driving part and a controlling part, an easily exchangeable member, one part of which consists of a feed or ratchet wheel co-operating with the feed device of the operating member, whilst the other part comprises a control wheel of which the periphery is composed of projecting edges and inverted surfaces.

A sliding member which is adjustable in height by the control wheel and which, in dependence on the position of the control wheel, lies above or in the path of movement of the operating member may advantageously act as the coupling member between the latter and the cutter bolt that acts on the perforating cutters. A lever operating the feed member is preferably effective in both of its directions of movement and may engage by means of a rotatably mounted roller a stationary ledger plate, the roller being so mounted as to rotate automatically during the feed movements of the lever. The roller is preferably mounted in a recess in the operating lever, since any colouring matter that may be picked up will then be to a certain extent rubbed off by the rotation of the roller in its enclosed recess, or on the ledger plate.

The invention is illustrated by way of example in the accompanying drawings, in which—

Fig. 1 shows a perforating device seen from the side.

Fig. 2 is a top view of Fig. 1.

Fig. 3 is an end view, as seen from the side A, of Fig. 1.

Fig. 4 is an end view, as seen from the side B, of Fig. 1.

Fig. 5 is a vertical longitudinal section through the perforating device, showing the coupling member *l* which is movable in a vertical and horizontal direction between the operating bolt *e* and the cutter bolt *c*.

Fig. 6 is a vertical section through the perforating device, showing the operating lever *b*, the operating bolt *e* and *m*, and the spring *k* supporting the coupling member *l*, as seen from the side A of Fig. 1.

Fig. 7 is a vertical longitudinal section similar to Fig. 5 and shows more particularly the pawl *f* of the operating bolt *e*.

Fig. 8 is a vertical section through the perforating device, showing the ratchet wheel *g*, the control wheel *h* and the pawl *f*, as seen from the side B of Fig. 1.

Fig. 9 is the same as Fig. 5, except that the ratchet wheel *g* and the control wheel *h* are shown in the position in which the coupling member *l* is pressed down into its coupling position.

The operating lever *b* pivots on an axle *c* mounted in the casing *a*. At the end of the operating lever *b* which projects through the casing *a* a roller *d* is rotatably mounted, for example in a suitable recess (see Figs. 1, 5 and 7). The arm of the operating lever *b* projecting into the casing actuates the operating bolt *e* which is displaceable against a spring *p* (see Figs. 5 to 9). The operating bolt *e* has a laterally extending part *m* and, at the end facing away from the operating lever *b*, carries a pawl *f* which can turn in one direction only.

Above the operating bolt *e* are mounted, on an axle *i*, a ratchet wheel *g* and a control wheel *h* which is fixed to the ratchet wheel *g*. The ratchet wheel *g* co-operates with the pawl *f* of the operating bolt *e* (see Fig. 7), whilst the control wheel *h* actuates a coupling member *l* which moves along a spring *k* fixed at one end and bent into a U-shape (see Figs. 5 and 8). The periphery of the control wheel *h* is composed of mutually abutting, curved surfaces which are convex with respect to the axis of rotation (see Figs. 5 and 7).

When one of the inwardly curved surfaces of

the control wheel *h* presses against the coupling member *i* carried by the free end of the spring *k* (see Fig. 5), the coupling member will stay, during any displacement of the operating bolt *e*, 5 above the part *m*, and will thus not be carried along with the bolt *e*, nor will it displace the cutter bolt *o*. On the other hand, when one of the projecting edges of the control wheel *h* presses against the spring *k* carrying the coupling 10 member *i*, the coupling member will, owing to the flexibility of the spring *k*, be brought into the path of the part *m* of the control bolt *e* and will be carried along by the bolt *e* when actuated by the operating lever *b*, thus actuating the cutter 15 bolt *o*.

The method of operation of the novel device is as follows:

When, under the influence of the printing or other installation to the perforating device, the 20 roller *d* comes into contact with the ledger plate, the lever *b* will rotate anti-clockwise, thereby displacing the control bolt *e*, *m* against the spring *p*. If now the control wheel *h* be in the 25 position shown in Fig. 5, in which one of its inverted surfaces presses against the spring *k*, that is to say, against the coupling member *i* carried displaceably on the spring *k* the coupling member *i* will stay above the path of the part *m* of the operating bolt *e*, and will thus not be 30 carried along during the displacement of the operating bolt or actuate the cutter bolt *o*. The perforating cutters will accordingly stay in their sheaths. Now, when the roller *d* of the operating lever *b* is disengaged from its ledger plate, the 35 spring *p* will push the operating bolt *e*, *m* back into its starting position. At the same time the pawl *f*, which is effective only on the return path of the operating bolt *e*, will move the ratchet wheel *g*, which is fixed to the control wheel *h*, 40 one step forward.

When, however, during the forward movement 45 of the operating bolt *e*, *m* the control wheel *h* is in the position shown in Fig. 9, one of the projecting edges of the control wheel *h* presses the spring *k* or the coupling member *i* carried displaceably on the spring *k* so far down that it comes into the path of movement of the part *m* of the operating bolt *e* and will, during the displacement of the operating bolt, be carried along 50 by the part *m*. This causes the cutter bolt *o* to be displaced so that the perforating cutters emerge against the action of springs tending to hold them in their sheath. When the pressure on the roller *d* is released, the operating bolt *e*, *m* will be 55 brought by the spring *p* into its starting position and will, thereby, as before by means of the pawl *f* move the ratchet wheel *g* one step forward. At the same time, owing to the pressure exerted by the springs which tend to hold the perforating 60 cutters in their sheath, the cutter bolt *o* will likewise be brought back into the starting position, thus also bringing the coupling member *i*, carried displaceably on the spring *k*, back into its starting position.

65 The perforations can be adapted to all requirements with the greatest facility, in dependence on the form of the easily exchangeable control wheel *h*.

I claim:

70 1. Perforating device for printing and other installations, adapted to actuate periodically perforating tools, comprising a casing, a control wheel rotatably mounted within the casing, an operating element adapted to be moved to and fro by an element of the installation, a spring-

loaded cutter bolt connected to the perforating tools, a coupling member integrally controlled by the control wheel and adapted to transfer the movement of the operating element in one direction to the cutter bolt when brought by the control wheel into a working position, and means adapted to advance the control wheel through a predetermined distance during the return movement of the operating element. 5

2. Perforating device as claimed in claim 1, 10 wherein there is mounted above the operating element an easily exchangeable member one part of which consists of a ratchet wheel co-operating with the advancing means of the operating element whilst the other part consists of 15 a control wheel of which the periphery is composed of projecting edges and inverted curves.

3. Perforating device for printing and other installations, adapted to actuate periodically perforating tools, comprising a casing, a control 20 wheel mounted rotatably within the casing, a ratchet wheel in fixed concentrical connection with the control wheel, an operating element arranged laterally of the ratchet wheel and being tangentially movable with respect to the ratchet 25 wheel against the action of a spring, said operating element carrying a laterally extending part on to the side of the control wheel and a feed-pawl adapted to move the ratchet wheel in one direction, a coupling member mounted on a 30 spring in such a manner that it may take a protruding or a non-protruding position with respect to the control wheel, in the protruding position extending into the path of the laterally extending part of the operating element, a lever 35 swingably mounted within the casing and having a part projecting through the casing adapted to be influenced by an element of the installation and an arm projecting into the casing and adapted to move the operating element in both 40 directions, and a cutter bolt slidably mounted within the casing and separated from the laterally extending part of the operating element by a distance adapted to receive the coupling member in its protruded position. 45

4. Perforating device for printing and other installations, adapted to actuate periodically perforating tools, comprising a casing, a control wheel rotatably mounted within the casing, an operating element adapted to be moved to and fro by an element of the installation, a spring-loaded cutter bolt connected to the perforating tools, a coupling member controlled by the control wheel and adapted to transfer the movement of the operating element in one direction to the 55 cutter bolt when brought by the control wheel into a working position, means adapted to advance the control wheel through a predetermined distance during the return movement of the operating element, said operating element having a driving part and a controlling part of which the controlling part is provided with a feed device and the driving part consists of a laterally extending part of the operating element and acts on the cutter bolt through the coupling 60 member. 65

5. Perforating device for printing and other installations, adapted to actuate periodically perforating tools, comprising a casing, a control wheel rotatably mounted within the casing, an 70 operating element adapted to be moved to and fro by an element of the installation, a spring-loaded cutter bolt connected to the perforating tools, a coupling member controlled by the control wheel and adapted to transfer the move- 75

ment of the operating element in one direction to the cutter bolt when brought by the control wheel into a working position, means adapted to advance the control wheel through a predetermined distance during the return movement of the operating element, the coupling member being a sliding part which is adjustable in height by the control wheel.

6. Perforating device for printing and other installations, adapted to actuate periodically perforating tools, comprising a casing, a control wheel rotatably mounted within the casing, an operating element adapted to be moved to and fro by an element of the installation, a spring-loaded cutter bolt connected to the perforating tools, a coupling member controlled by the control wheel and adapted to transfer the movement of the operating element in one direction to the cutter bolt when brought by the control wheel into a working position, means adapted to advance the control wheel through a predetermined distance during the return movement of the operating element, the coupling member being slidably mounted on a spring and adjustable 25 in height by the control wheel.

7. Perforating device for printing and other installations, adapted to actuate periodically perforating tools, comprising a casing, a control wheel rotatably mounted within the casing, an operating element adapted to be moved to and fro by an element of the installation, a spring-loaded cutter bolt connected to the perforating tools, a coupling member controlled by the control wheel and adapted to transfer the move-

ment of the operating element in one direction to the cutter bolt when brought by the control wheel into a working position, means adapted to advance the control wheel through a predetermined distance during the return movement of the operating element, the operating element being held by a spring in engagement with a lever swingably mounted in the casing and having a part projecting through the casing adapted to be influenced by the element of the installation.

8. Perforating device for printing and other installations, adapted to actuate periodically perforating tools, comprising a casing, a control wheel rotatably mounted within the casing, an operating element adapted to be moved to and fro by an element of the installation, a spring-loaded cutter bolt connected to the perforating tools, a coupling member controlled by the control wheel and adapted to transfer the movement of the operating element in one direction to the cutter bolt when brought by the control wheel into a working position, means adapted to advance the control wheel through a predetermined distance during the return movement of the operating element, the operating element being held by a spring in engagement with a lever swingably mounted in the casing and having a part projecting through the casing adapted to be influenced by the element of the installation, and a roller interposed between the element of the installation and the projecting part of the lever and rotatably mounted within the lever.

CARL FUNCKE.
